UNITED STATES PATENT OFFICE.

ROBERT GREENE, OF LONDON, ONTARIO, CANADA.

ROADWAY.

1,379,813.

Specification of Letters Patent. Patented May 31, 1921.

Application filed October 29, 1920. Serial No. 420,506.

To all whom it may concern:

Be it known that I, ROBERT GREENE, a subject of the King of Great Britain, and a resident of the city of London, in the county 5 of Middlesex, Province of Ontario, Canada, have invented certain new and useful Improvements in Roadways, of which the following is a specification.

My object in the present invention is to 10 devise a roadway which may be cheaply constructed and which will still afford most of the advantages of a road of the so-called "permanent" type, that is, roads formed mainly of concrete with or without a bituminous or asphaltic surface.

I attain my object by substituting for the continuous surface of the ordinary road two relatively narrow strips of concrete or the like, the crown and haunches of the road 20 being formed of less durable and cheaper material such as gravel or waterbound macadam. Such strips or "twin trails" as I term them are, however, ordinarily impracticable owing to ruts forming at the edges 25 of the strips in the softer material of the crown and haunches. An important further feature of my invention therefore lies in the means I employ for the prevention of such ruts.

30 The invention is illustrated in the accompanying drawings in which—

Figure 1 is a plan view of a roadway constructed in accordance with my invention; and

35 Fig. 2 a cross section of part of the same. In the drawings like numerals of reference indicate corresponding parts in the different figures.

In its preferred form the roadway 40 comprises two relatively narrow strips 1 of concrete or other road material of a type recognized as substantially permanent. These strips are laid on any usual foundation. Exterior to these strips are the haunches 2, 45 which will be of suitable road surfacing material generally recognized as of inferior durability, such, for example, as gravel or water bound macadam, though, of course, bituminous surfaced materials might be employed. Generally speaking, however, where it is desired to attain a maximum of utility 50 having regard to cost, the haunches will be formed of gravel. The crown 3 between the strips 1 will usually be formed of any material suitable for the haunches 2.

The sides of each of the strips 1 will be formed of a continuous series of triangular

projections 3, that is to say, the sides of adjacent projections meet so that a series of similar projections 5 are formed in the 60 gravel when the latter is in place.

The result of this arrangement is that the gravel is held between the projections of the concrete, and the level of the road is preserved. I find by experience that the 65 gravel packs in the serrations of the concrete in such a way that ruts or depressions are not formed.

It will be evident, of course, that the same 70 form of edging may be applied to a concrete or similar roadway which extends completely across the road and which is provided with haunches of a different material.

What I claim as my invention is:—

1. In a road surface, a longitudinal strip 75 of hard road material and an adjacent strip of relatively softer or less permanent material, the hard material having a continuous series of triangular projections formed integral therewith along its edge and forming triangular recesses into which the softer material of the adjacent strip extends. 80

2. In a road surface, a longitudinal strip of hard road material and an adjacent strip of relatively softer or less permanent material at each side thereof, the hard material having a continuous series of triangular projections formed integral therewith along each side and forming triangular recesses 85 into which the softer material of the adjacent strip extends. 90

3. A road surface comprising two parallel wheel strips of hard or permanent road material and haunches and crown of relatively softer or less permanent material, each edge 95 of each of the wheel strips having a continuous series of triangular projections formed integral therewith and forming triangular recesses into which the softer material of the adjacent strip extends. 100

4. A road surface comprising two parallel wheel strips of concrete and haunches and crown of gravel, each edge of each of the wheel strips having a continuous series of triangular projections formed integral 105 therewith and forming triangular recesses into which the gravel of the haunches and crown extends.

Signed at London, this 14th day of October, 1920.

ROBERT GREENE.
